RODLESS PUMP

Walter N. Huff, Harwood, Tex.

Application May 21, 1936, Serial No. 81,110

3 Claims. (Cl. 103—44)

This application is a continuation in part of applicant's applications Serial Nos. 64,920 and 80,211, filed February 20, 1935 and May 16, 1936 respectively, and this invention relates to pumps, especially those used in oil wells and the object thereof is to produce a pump of simple construction, which is durable and efficient.

One object of the invention is to eliminate the use of long lifting rods which in wells of great depth are a great disadvantage.

Another object of the invention is to use pressure generated by a pump at the surface to compress a spring at the bottom of the well and use the energy of expansion thus stored in the spring 15 to force the fluid above the surface. Other objects will appear from the following description.

The invention will be clearly understood from the following detailed description, taken in connection with the drawing, in which:

Fig. 1 is a vertical cross-section with parts shown in elevation.

Fig. 2 is a cross-section looking in the direction of the arrows on line 2—2 of Fig. 1.

Fig. 3 is a cross-section looking in the direction 25 of the arrows on line 3—3 of Fig. 1.

Fig. 4 is a cross-section looking in the direction of the arrows on line 4—4 of Fig. 1.

The tubing reaching from the surface to a short distance above the bottom of the well, is 30 designated by the numeral 1. A cylinder 2, herein called the pumping cylinder, is connected to said tubing by a valved collar 3 to be described later.

To the lower end of this pumping cylinder 2 is 35 connected, by means of a flanged stop collar 4, a perforated cylinder 5 to the lower end of which a second flanged collar 6 is attached as by screw-threads. All of said collars are internally screw-threaded at each end as shown for attachment of 40 the parts, and each of the stop collars has an internal flange for a purpose to be described later.

To the bottom collar 6, is attached any desired 45 footing. At the top of the tubing 1 is secured a cap 7 having an internally screw threaded aperture therein.

The collar 3, is of substantial length and near the upper end just below the screw-thread are fingers 3' extending toward the center. These fingers serve as a stop to the upward motion of a 50 floating hollow cylinder 8 described below. Near the lower end of the collar 3, a valve seat 3" extends toward the center leaving a substantial opening about the axis for the passage of the fluid.

The floating cylinder 8 is of much smaller diameter than the tubing, a fact of the greatest im-

portance in the operation of the device. An external flange on the lower end of the floating cylinder forms a valve 9 seating on the seat 3". The movement of the floating cylinder 8 is limited by contact of the valve 9 with the fingers 3' and 5 with the valve seat 3".

Within the floating cylinder 8 is a fluid-tight piston 10 and attached to this piston preferably by screw threads is a rod 11 extending below the collar 3 into the pump cylinder 2. A cage 12 is 10 attached to the lower end of said rod 11 and to a valved piston 13 capable of sliding fluid-tight in said pump cylinder. A check valve 14, opening upwardly is confined by the cage 12 and when seated closes the aperture in valve piston 13. 15

A second cage 15 is attached to the bottom of the piston and to this second cage a preferably hollow lifting rod 16 is attached. While these various attachments are shown as formed by screw threads, any equivalent means of attachment may of course be used. 20

The lifting rod passes through the collar 4 and well down into the perforated cylinder 5. On this rod within the perforated cylinder is screwed or otherwise fixedly attached, a perforated washer 25 17 shown in detail in Fig. 4.

A strong heavy coil spring 18 is confined within the perforated cylinder and bears against the perforated washer at one end and an inwardly extending flange on the collar 6. As this spring 30 reacts with great force after compression, a light cushioning spring 19 is confined in the upper portion of the perforated cylinder bearing on the washer 17 and preferably attached thereto and bearing on the other end, at least when compressed, on the flange of the collar 4. 35

The apparatus for applying pressure to the fluid in the tube 2, releasing said pressure and affording delivery to the oil is above the surface of the ground, and will now be described. This 40 apparatus comprises a pump 20, single or multiplex and operated by a source of power not shown.

The pump has an accumulator 21 and a supply 45 pipe 22 leading from a source of supply 23.

The accumulator may be of any type and may comprise weights lifted by the pressure or air confined and compressed by the liquid operated on by the pump.

Communicating with the accumulator is a pipe 50 25 leading to a valve casing 26 having three lateral openings and a revoluble three-way valve 27 therein for putting desired openings in communication with each other.

The lower opening of said valve casing has 55

attached thereto a pipe 28, the lower end of which is attached to the cap 7. The tubing 1 is thus in communication with the pump and accumulator in one position of the valve, the 5 delivery being shut off, while in another position, as shown, the tubing 1 is in communication with the delivery pipe 29, leading to a storage tank 30.

The three-way valve is automatically turned through ninety degrees by any convenient mechanism as a link connection 31 shown, or a cam, actuated by any convenient source of power. The 10 pump may be, but is not necessarily, used for this purpose. T's 32 and 33, respectively, forming parts of pipes 25 and 28 serve to connect a 15 by-pass 34 to said pipes. A check valve 35 opening upwardly in the by-pass serves to correct any tendency to a vacuum above the three-way valve.

The operation of the device is as follows:

20 After some strokes of the pump the pressure rises, the valve 27 is automatically turned to place tubing 1 and the accumulator in communication, the delivery being thereby shut off.

The fluid pressure acting on the piston 10 25 forces the same downward and also closes valve 9 thus cutting off communication between the tubing 1 and the cylinders below.

As the piston 10 descends, fluid must enter the tubing from the source of pressure and the 30 volume of that fluid will be the internal cross-section of the floating cylinder 8 multiplied by the vertical movement of the piston 10. Piston 13 is moved downward through the same distance as piston 10. Valve 14 is raised and fluid 35 flows into the upper part of pumping cylinder 2. The volume of fluid thus entering the upper part of pumping cylinder 2 is equal to the internal cross-section of the cylinder 2 multiplied by the distance through which the piston 13 moves 40 which is equal to the distance through which the piston 10 moves.

At the end of the downward stroke, the volume 45 of fluid above the piston 13 is increased by the difference between the aforesaid volumes. Through rod 16 and washer 17, spring 18 in the perforated cylinder 5 has been compressed by the downward movement of piston 10.

The pressure on the fluid at the surface of tubing 1 is automatically released by oscillating 50 the valve to close the communication with the source of pressure and open the communication with the delivery.

The energy stored in the spring 18, raises the 55 washer 17 and the piston 13. The valve in the piston 13 closes, valve 9 opens and fluid is forced through the delivery pipe. As the piston 13 reaches the upper limit of its stroke valve 27 is oscillated to close communication with the delivery pipe and open communication with the 60 source of pressure. The cycle of operations is then repeated.

In the operation of this device the fluid below 65 the pumping piston is never subjected to the pressure of the pressure source and hence oil from the well may flow freely into the perforated cylinder to take the place of that removed. Moreover, largely owing to this fact, the casing usual in the well may if desired, be dispensed with.

70 Having fully described my invention and the operation thereof, what I claim is:

1. In an apparatus for pumping, a continuous tube, a source of fluid pressure, means for putting said continuous tube alternately in communica-

tion with said source of fluid pressure and with the atmosphere, a valve seat rigid in the lower part of said continuous tube, a movable hollow cylinder of substantially less diameter than the continuous tube, having a flange forming a valve 5 for said valve seat, a piston in said hollow cylinder, stop means limiting the vertical movement of said hollow cylinder, a rod connected to said piston, a valved piston slideable fluid-tight in said continuous tube attached to the lower end of 10 said rod, a lifting rod attached to said last named piston, a perforated washer rigidly attached to said lifting rod, a heavy coiled spring bearing against said washer, an internal flange near the lower end of said continuous tube against which 15 the other end of said spring bears, the portion of the continuous tube below said valved piston in its lowest position being perforated, whereby, on placing in communication the continuous tube and the pressure source, the pistons will be moved 20 downward and the spring compressed and on placing in communication the continuous tube and the atmosphere the spring will be released 25 to expel fluid from the continuous tube.

2. In an apparatus for pumping oil from a 25 well, a fluid-tight structure comprising tubing, a hollow pumping cylinder of substantially the same diameter as said tubing, a collar having an internal valve seat at its lower end and internal 30 stop fingers at its upper end, secured to the lower end of said tubing and to the upper end of said pumping cylinder, a floating hollow cylinder of substantially smaller diameter than the tubing extending into said collar and having a flange at its lower end to seat on said valve seat, a fluid-tight piston in said floating cylinder, a rod depending from said piston and extending into said pumping cylinder, a fluid-tight valved piston in said pumping cylinder and connected to said rod, a check valve on said piston opening separately, 35 a perforated cylinder and a second collar having an internal flange and connecting said perforated cylinder to said pumping cylinder, a lifting rod connected to said valved piston and extending into said perforated cylinder, a perforated washer fixed on said lifting rod, a heavy coil spring in said perforated cylinder bearing 40 at its lower end on said perforated cylinder and at its upper end on said perforated washer, and a lighter coiled spring bearing at its lower end 45 on said perforated washer and at its upper end on the flange of said second collar whereby alternate application and release of pressure at the upper portion of the tubing pumps fluid from the well.

3. In apparatus for pumping oil from wells, a continuous tube, means for maintaining a fluid under pressure, communicating means from said fluid under pressure to the upper portion of said continuous tube, a three-way valve in said communicating means for opening said continuous tube to the fluid under pressure or cutting off said continuous tube from said fluid under pressure and opening said continuous tube to the atmosphere and means entirely within said continuous tube for storing the energy given out by the fluid under pressure when in communication with the continuous tube and applying the same to raising oil in the well when said continuous tube is placed in communication with the atmosphere, and a by-pass around the three-way valve and a check valve therein opening toward said fluid under pressure.

WALTER N. HUFF.
